(57) **CLAIM**

The ornamental design for a laptop protector, as shown and as described.

DESCRIPTION

FIG. 1 is a front perspective view of a laptop protector in accordance with the present invention;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a front perspective view of the laptop protector in use.
The broken lines in FIG. 8 represent environmental elements which form no part of the claimed design.

1 Claim, 6 Drawing Sheets
